ATTYS.

UNITED STATES PATENT OFFICE.

GROVE R. MERRIMAN, OF AKRON, OHIO, ASSIGNOR TO JOHN R. VANDER PUTTEN, OF AKRON, OHIO.

BRUSH FOR CARPET-SWEEPERS.

1,350,664.

Specification of Letters Patent. Patented Aug. 24, 1920.

Application filed October 27, 1919. Serial No. 338,530.

To all whom it may concern:

Be it known that I, GROVE R. MERRIMAN, a citizen of the United States, residing at Akron, in the county of Summit and State 5 of Ohio, have invented a new and useful Brush for Carpet-Sweepers, of which the following is a specification.

This invention relates to improvements in devices for brushing and cleaning floors and 10 floor covering, such as carpets, rugs and the like and more especially to a brush carried in said device.

The objects of the invention are to provide a brush so constructed that it will operate with the least resistance and will not hinder the free and easy movement of the device over the surface to be cleaned, to form the brush in two sections independently rotatable with reference to each other, 15 to provide means for easily and readily placing the brush in the sweeper or removing it therefrom; and to generally improve and simplify devices of this character.

With these objects in view the invention 20 consists in the novel construction and arrangement of parts, hereinafter described, illustrated in the accompanying drawings, and particularly pointed out in the appended claims, it being understood that various 25 changes in the form, proportions, size and minor details of construction may be made within the scope of the appended claims, without departing from the spirit or sacrificing any of the advantages of the invention. 30

The invention thus set forth in general terms is illustrated in the accompanying drawings forming parts hereof, in which—

Figure 1 is a perspective view of the lower 35 portion of the sweeper casing showing the brush assembled therein.

Fig. 2 is a plan view of a portion of the same, parts being shown in section for the purpose of illustration.

A practical embodiment of the invention 40 is disclosed in the accompanying drawings, forming a part of this specification in which similar numerals of reference indicate corresponding parts throughout the several 45 views.

The numeral 1 indicates the lower portion 50 of a sweeper casing which may be of any well known design and as shown in the drawings is provided with the compartments 55 2 at its ends for the purpose of receiving the

drive wheels 3 which are pivoted within said compartments in the usual manner. It should be understood that the type of 60 sweeper casing shown in the drawings forms no particular part of the present invention, the brush embodying the invention being adaptable to any usual and well known form of portable sweeper.

Bearings 4 are mounted upon the casing as shown, the shafts 5 being journaled in 65 said bearings. Small pulley 6 is mounted upon each shaft and connected to the adjacent drive wheel 3 by means of a belt 7.

Each of the shafts 5 is provided with a flattened inner extremity 8 adapted to be 70 received in the similarly shaped end 9 of the tubular brush shaft 10. The brushes 11 are formed upon the brush-shafts 10 in any usual and well known manner.

The inner extremities of each of the brush 75 shafts 10 are extended into the tubular coupling member 12 being slidably mounted through apertures in the end caps 13 which are provided upon said coupling member. A pair of spaced washers 14 and 15 are fixedly 80 attached to each of the brush shafts, these washers being slidable within the tubular coupling member and arranged to fit snugly therein, allowing the brush shafts to move axially toward and from each other within 85 the tubular cup member and preventing any side member of the brush shafts within the coupling member.

A ball 16 engages the inner open end of 90 each of the brush shafts and fits freely within the interior of the tubular coupling member, a spring 17 engaging both of said balls and normally holding the brush shafts in the positions best illustrated in Fig. 2, the washers 14 thereon being held in engagement with the caps 13 of the coupling member. In order to remove the brush 95 from the sweeper or replace the same therein, it is only necessary to grasp the brushes and move them axially toward each other, compressing the springs 17 sufficiently to allow the outer ends of the brush shafts to clear the ends of the axles 5. Upon releasing the grip upon the brushes the spring will immediately force them back into the 100 position shown in Fig. 2, the washers 14 limiting the outward movement of the brush shafts.

In operation it will be seen that the 105 brushes are rotatable independently of each 110

other and thus the sweeper may be turned in any direction without interfering with the action of the brushes as each brush is driven independently by the adjacent drive wheel. It will thus be seen that the sweeper may be moved or turned at times so that only one brush will be rotated or that each brush may be rotated in an opposite direction from the other and the driving wheels will never be locked when the sweeper is turned as often happens in the usual type of sweepers, in which a single brush is driven by both drive wheels.

Although the drawings and above specification disclose the best mode in which I have contemplated embodying my invention I desire to be not limited to the details of such disclosure, for, in the further practical application of my invention, many changes in form and construction may be made, as circumstances require or experience suggests, without departing from the spirit of the invention, within the scope of the appended claims.

25 I claim:—

1. In a carpet sweeper, a pair of axially aligned independently rotatable brushes and a coupling member connecting the inner extremities of said brushes, said brushes arranged for axial movement with relation to each other.
2. In a carpet sweeper, a pair of axially aligned independently rotatable brushes, and a tubular coupling member rotatably and axially movable upon the inner extremities of said brushes.
3. In a carpet sweeper, a pair of axially

aligned independently rotatable brushes, a tubular coupling member rotatably and axially movable upon the inner extremities of 40 said brushes, and a resilient member within said coupling engaging the inner extremities of the brushes.

4. In a carpet sweeper, a pair of axially aligned rotatable brushes, a tubular coupling 45 member within which the inner ends of said brushes are slidably and rotatably mounted, balls engaging the inner ends of said brushes and a spring located between said balls.

5. In a carpet sweeper, a pair of axially aligned rotatable brushes, a tubular coupling member provided with end caps through which the inner ends of said brushes are slidably and rotatably mounted, and a 55 spring located between said brushes.

6. In a carpet sweeper, a pair of axially aligned rotatable brushes, a tubular coupling member provided with end caps through which the inner ends of the brushes are rotatably and slidably mounted, balls engaging the inner ends of said brushes and a 60 spring located between said balls.

7. In a carpet sweeper, a pair of axially aligned rotatable brushes, a tubular coupling 65 member provided with end caps through which the inner ends of the brushes are rotatably and slidably mounted, balls engaging the inner ends of said brushes, a spring located between said balls and independent 70 means for rotating each brush.

In testimony that I claim the above, I have hereunto subscribed my name.

GROVE R. MERRIMAN.
